[57] **CLAIM**

The ornamental design for a combined winch mount and draw bar adapter for vehicles, substantially as shown.

DESCRIPTION

FIG. 1 is a perspective view of a combined winch mount and draw bar adapter for vehicles showing my new design;

FIG. 2 is a bottom plan view thereof;

FIG. 3 is a side elevational view thereof;

FIG. 4 is a side elevational view thereof opposite to that

shown in FIG. 3;

FIG. 5 is a front elevational view thereof; and

FIG. 6 is a rear elevational view thereof.
